UNITED STATES PATENT OFFICE.

ARCH EUDY, OF RIVERSIDE, CALIFORNIA.

COMBINATION-TOOL

1,132,248.

Specification of Letters Patent. Patented Mar. 16, 1915.

Application filed March 31, 1913. Serial No. 757,747.

To all whom it may concern:

Be it known that I, ARCH EUDY, a citizen of the United States, and residing in the city of Riverside, county of Riverside, and State of California, have invented a new and useful Improvement in a Combination-Tool, of which the following is a specification.

This invention relates to combination tools, and the principal object is to provide a convenient tool to handle ice provided with a pick and a shaving device.

It is also an object to provide the handle of an ice pick, formed of hinged sections, one of which is provided with a cap lifting hook, and the other portion holds the shaving device together with a foldable cork screw and can opener.

In the drawings accompanying this specification—Figure 1 is a side elevation of the pick with the section of the handles closed. Fig. 2 is a longitudinal section through the shaver portion of the handle showing the can opener opened up. Fig. 3 is another sectional view of the handle showing the cork screw located in its recess. Fig. 4 is a view showing the section provided with a hook applied to a bottle cap. Fig. 5 is a face view of the body section of the handle, the hinged section being removed. Fig. 6 is a section on the line 6—6 of Fig. 1 viewed in the direction indicated by the arrows.

More specifically in the drawings, 7 designates a cylindrical ice pick having the sharpened point 8, the blunt end of the pick being secured in the body section 9 of the handle and secured therein by any suitable means not shown. This body section of the handle together with the hinged section 10, when folded together and locked in position by suitable catch, not shown, form the usual and conventional form of handle of general cylindrical configuration.

The line of separation of the sections is preferably carried through the handle in such a manner that the hinged section overlaps or forms the hook 11, including the palmar end of the handle, this hook 11 being provided with a recess 12 opposite the point of the hook which engages with a bottle cap by the corner formed by the depression, and when inserted under the crimped edge of a bottle cap will lift the same and uncork the bottle.

The body portion 9 of the handle is pro-

vided with a plurality of recesses, the central and larger of which 14 forms a chamber for the insertion of the scraper 15 secured by means of the screws 16, in which may be caught the particles of ice removed by the teeth 17 formed on the exposed edge of the blade. These teeth preferably extend as shown, beyond the covered inner face of the body portion. This blade is preferably of the general triangular form, and is overlapped slightly by walls 18 and 19 of the two other recesses formed in the inner face of the body member, which are adapted to receive a cork screw 20 and the can opener 21. The cork screw is preferably pivoted on a pivot pin 22 carried through the wall 19 and the exterior wall of the body portion. The can opener 21 is similarly pivoted, preferably at the end of the slot nearest to the palmar end of the handle, the opener being provided with the puncturing and pivot point 23, which is adapted to enter the center of a can, and cutting stud 24, which is adapted to be carried around a circumference struck from the engagement of the point 23 as a center. This pointed tool can also be used to pry off the wire securing means around bottle corks, and for other well known uses. To secure the two sections of the handle, a hinge 25 is provided.

In the operation of the pick, large portions of the ice are adapted to be separated by means of punctures into the material made by the pick 7, while irregularities caused by unusual fracture of the ice, or when it is desired to scrape off small portions of shaved ice for beverages, the pick 7 is grasped in the hand, including and holding the section 10 in open position, so that the sharpened teeth may be projected over the surface of the ice cake in a direction away from the operator, the angular position of the blade determining the depth of the cut made into the surface.

What I claim is:

1. In a combined ice-pick and shaver, a handle formed with a recessed opening on one side thereof, an outwardly curved ice shaver rigidly mounted on said handle within the recess with its cutting edge normally projecting beyond the outer edges of the recess, and a hinged member having a recessed underside hinged on said handle and adapted to close the recess in the latter to conceal the ice shaver.

2. In a combined ice pick and shaver, a handle on which the pick is mounted formed with a recess opening at the end of the handle portion and on one side thereof, an
5 outwardly curved ice shaver secured in said handle with its cutting edge adapted to extend beyond the sides of the recess, a hinged member on said handle portion adapted to close the open side and end of
10 the recess in the handle portion to conceal

the ice shaver and coöperate with the handle portion to complete the handle.

In witness that I claim the foregoing I have hereunto subscribed my name this 15th day of March, 1913.

ARCH EUDY.
